WINDMILL FOR ADVERTISING AND
DEVELOPING POWER

Wylie M. Holland, Carrollton, Ga.

Application June 30, 1933, Serial No. 678,501

2 Claims. (Cl. 40—39)

This invention relates to a windmill and it aims to provide a multiplicity of vanes or blades which function as advertising means and also to produce motion under the action of the wind.

- 5 A particular object is to provide novel vanes which may have advertising matter on both sides thereof and which are rotatable in order to present various combinations of advertising signs or data.
- 10 Another object is to provide a novel construction which will permit the use in whole or in part, especially as regards the gearing and shafting, parts of old or junk automobiles, in order to minimize the cost of manufacture.
- 15 The more specific objects and advantages will become apparent from a consideration of the description following taken in connection with accompanying drawings illustrating an operative embodiment.
- 20 In said drawings:—
- Figure 1 is a view in side elevation showing my improved windmill;
- Figure 2 is a plan view of said windmill;
- Figure 3 is an enlarged detail partly in plan 25 and partly in section, showing the gearing for causing rotation of the vanes;
- Figure 3^a is a diagrammatic detail disclosing the structure of Figure 3 with the frame as a whole rotated through 180 degrees;
- 30 Figure 4 is a detail cross sectional view taken on the line 4—4 of Figure 5;
- Figure 5 is an enlarged view primarily in vertical section, showing the drive gearing and shafting;
- 35 Figure 6 is a vertical sectional view through the differential; and
- Figure 7 is a vertical sectional view on an enlarged scale of a portion of the drive.
- Referring specifically to the drawings, 10 designates a suitable skeleton frame of wood, metal, or other material, and of any appropriate size, carrying blades or vanes at 11 mounted on shafts 12 which are journaled in the frame 10 for rotation on vertical axes. Although four of the vanes 40 are shown, any desired number may be used. Such vanes are adapted to have advertising matter delineated on one or both sides thereof as preferred, so that the different signs and combinations thereof will come into view during rotation. Such vanes, however, always bear the relative angular relation shown in Figure 2 so as to be broadside with respect to and to point into the wind most advantageously.
- In addition to the vanes 11 having a rotary 45 movement on their axes 12, the frame 10 also
- bodily rotates on a vertical axis, being rigid with a shaft or axle as at 13. Power is derived through the impingement of the air upon the said vanes 11, in order to rotate the said frame. The frame carries a wheel like support 14, as a 5 rigid part thereof and journaled therein is an upright shaft 15 whose axis is coincident with that of the shaft 13. Keyed to shaft 15 is a spur gear wheel 16 with which are enmeshed planetary gear wheels 17 journaled as at 18, in turn 10 with which gear wheels 17 are enmeshed large planetary gear wheels 19. The gear wheels 19 are rigid on suitably journaled shafts 20. Said shafts 20 have cranks 21 which are pivoted at 22 to pitmen 23, in turn pivoted at 24 to cranks 25, 15 25', 25'' and 25''' on the aforesaid shafts 12. As a result, the rotation of the frame 10 rotates the vanes 11 in an orbit and the gearing causes said vanes to rotate on their individual axes. Said cranks 21 and 21' are always pointed in parallel 20 directions and their directions are reversed at each revolution of the frame so that the wind blows against one side of the vane at the end of one revolution of the frame and against the other side of the frame at the end of the next revolution. Also, cranks 25 and 25'' are always pointed 25 in parallel directions, while cranks 25' and 25''' are always pointed in parallel directions. The device thus serves as a windmill for generation 30 of power and also as an effective advertising medium in view of the different signs and advertising surfaces and combinations thereof which are brought into view. The parts described thus constitute a mill.
- Shaft 13 being driven by the mill, drives gearing 26, as best shown in Figure 7, the aligned shaft 13^a being held from rotation by any suitable means such as bar 13^b that may be fixed in any suitable manner, in turn driving a horizontal shaft 27 which is releasably coupled in any 40 suitable manner as at 28, to a power take-off shaft 29. Such shaft 29 may have a pulley 30 thereon, for example, adapted to drive a generator, magneto or any other work desired.
- A governor and weather-vane construction is 45 employed in connection with the device to afford additional advertising surfaces and to govern the speed of operation of the mill, the same being thrown into and out of gear automatically and particularly maintaining the speed below a pre-determined minimum. To this end, a beam 31 is journaled on the upper portion of the shaft 15, having an arrow 32 at one end, and a vane 33 at the other end. Such beam and vane at opposite sides thereof may contain advertising data 50 55

or signs so that the maximum surface may be used for advertising purposes. A gear device 34 is in part connected to the beam 31 and in part connected to the shaft 15. Said device has gears 34' and 34'', the former being rigid with shaft 15 and the latter gear being rotatable on said shaft 15. Below a predetermined velocity of rotation, the position of shaft 15 is fixed relative to beam 31 and gear device 34; and above such velocity, 10 the centrifugal force on members 49 will cause rods 46 to slide yoke 42 downward on shaft 15, thus rocking L-shaped arm 40 at pivot 41, pulling rod 39, rod 36, crank 35 and turning shaft which is keyed to the only spider gear of differential in 15 use for operative purposes of mill, thereby causing shaft 15 to be turned slightly relative to gear device 34 and beam 31, thus changing position of spur gear 16 and its associated gears, which determines the position of vanes 11 relative to 20 the wind current.

A link or connecting rod 39 is pivoted to lever 37 and also to a bell crank lever 40 pivoted at 41, to a part of the beam 31 and in turn operatively connected to a yoke 42 engaging in a groove of a 25 collar 43 which is vertically slidable along the shaft 15. To said collar, links or connecting rods 44 are pivoted at 45 and in turn they are pivoted at 46 to bell crank levers 47 pivoted at 48 on the frame 10. The levers 47 carry weights at 30 49. Such weights 49 may be discarded pistons suitably filled or weighted with lead or other metal or material. The differential 34 is normally held in position on beam 31, that is, the case of the differential is bolted to beam 31. 35 The shaft 15 is held in position normally relative to gear device case 34 and beam 31 by the weight of members 49 and their associated rods. The members 49 are of a predetermined weight so that such members 49 will operate through 40 centrifugal force as the mill rotates, in order to slide the sleeve 42 on the shaft 15 and actuate the pivoted L-shaped arm 40, and rod 39, lever 37, rod 36, thus turning shaft 35 and its associated spider gear roller, which is meshed 45 with upper axle gear 34' of said gear device 34, which is keyed to shaft 15. This mill can be made to run in reverse order by disjoining crank 35 from rod 36 and turning said crank one complete revolution, then rejoin or refasten crank 35 to 50 rod 36.

The shaft 13, gearing 26, shaft 27 and associated parts may be conveniently housed as at 50. The frame 10 carries a drum 51 in which a normally contracted brake band 52 is disposed. 55 Operating means 53 are provided for the brake band in order to expand the same against the drum 51, in an emergency, to stop the rotation and operation of the mill.

Drum 51 is rigid with a wheel 54, for instance, 60 that wheel to which the drum is attached on the

automobile, and which element 54 in the present invention is a mounting for frame 10 and shaft 13.

Obviously the device may be made from specially manufactured parts. However, in use I find that it can advantageously and inexpensively 5 be made at least to a large extent from gearing and parts of discarded and junked automobiles. To this end, the parts 13, 51, 53, 26 and 27, may be the propeller shaft and rear end part of a Chevrolet Model 490. In fact the part 28 may 10 be brake drums from the same automobile or another. Likewise, the shaft 15 may be an axle from an automobile, for instance, a Ford Model T. The differential 34 may be parts taken from the same Model T Ford automobile. The gears 15 16 and 17 may also be parts of the Ford planetary transmission gearing.

It is obvious that the device may be mounted on any desired support or structure. For instance, a special stand or platform may be used 20 it may be secured on or within the roof of a dwelling, store, garage or other building, on a fence or otherwise.

Various changes may be resorted to provided they fall within the spirit and scope of the invention. 25

I claim as my invention:

1. A mill of the class described having a rotatable frame, vanes journaled on said frame adapted to be driven by the wind, means operable to cause rotation of the vanes relatively to the frame during rotation of the frame, said means including a shaft rising from the frame, planetary gearing connected to the shaft, crank and pitman means connecting the planetary gearing 35 and vanes, a vane journaled on said shaft, gearing at the top of said shaft positioning the last mentioned vane, and governor means operable by the rotation of the frame to control the operation of said last mentioned gearing. 40

2. A mill of the class described having a rotatable frame, vanes journaled on said frame adapted to be driven by the wind, means operable to cause rotation of the vanes relatively to the frame during rotation of the frame, said means including a shaft rising from the frame, planetary gearing connected to the shaft, crank and pitmen means connecting the planetary gearing and vanes, a vane journaled on said shaft, gearing at the top of said shaft positioning the last mentioned vane, governor means operable by the rotation of the frame to control the operation of said last mentioned gearing, including a sleeve 45 slidable on the shaft between the last mentioned vane and said planetary gearing, weighted elements to control the sliding of the sleeve, and lever and link mechanism operated by the sleeve and connected to the gearing. 55
